US00D862575S

(12) **United States Design Patent** (10) **Patent No.:** **US D862,575 S**
Liu (45) **Date of Patent:** **** Oct. 8, 2019**

(54) **GLASSES**

(71) Applicant: **SHANGHAI QINGSHENG NETWORK TECHNOLOGY CO., LTD.**, Shanghai (CN)

(72) Inventor: **Junyi Liu**, Shanghai (CN)

(73) Assignee: **SHANGHAI QINGSHENG NETWORK TECHNOLOGY CO., LTD.**, Shanghai (CN)

(**) Term: **15 Years**

(21) Appl. No.: **29/635,592**

(22) Filed: **Jan. 31, 2018**

(30) **Foreign Application Priority Data**

Jan. 5, 2018 (CN) 2018 3 0005261

(51) **LOC (12) Cl.** **16-06**

(52) **U.S. Cl.**

USPC **D16/326**

(58) **Field of Classification Search**

USPC D16/317, 300, 315, 326

CPC G02C 11/10; G02C 11/00; G02C 2200/08;

G02C 7/10

See application file for complete search history.

(57) **CLAIM**

The ornamental design for glasses, as shown and described.

DESCRIPTION

FIG. 1 is a front view of glasses, showing my new design;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The broken lines in the figures illustrate portions of the glasses which form no part of the claimed design.

1 Claim, 7 Drawing Sheets
